ELECTRIC SWITCH WITH PERMANENT-MAGNET BLOWOUT FIELDS

Bruce C. Wells, Buffalo, N. Y., assignor to Westinghouse Electric Corporation, East Pittsburgh, Pa., a corporation of Pennsylvania

Application June 23, 1951, Serial No. 233,136

9 Claims. (Cl. 200—147)

1

My invention relates to electric switches and more particularly to switch contact devices with permanent magnets to provide an arc blowout field.

Known devices, for the kind of switch contact arrangement I utilize, provide a single relatively large electromagnet mounted so that the two poles of the magnet are on opposite sides of the relatively movable contacts. If the arrangement is for a transfer switch where a movable contact moves in contact and out of contact with first one stationary contact and then another stationary contact, it is apparent that the arc on opening of the contacts will be blown first in one direction and then in another. Such operation is highly undesirable in some applications.

It is one broad object of my invention to effect a uniform blowout direction for an electric arc with reference to the elements of the switch structure.

It is a more specific object of my invention to provide an arc blowout in the same direction at the contacts of a vibrating contactor.

The objects recited are merely representative of other objects and advantages of my invention that will become more apparent from a study of the following specification and the accompanying drawings, in which:

Figure 1 is a plan view of an electromagnetic contactor provided with my invention;

Fig. 2 is a side view, partly in section, of the subject matter shown in Fig. 1;

Fig. 3 is a plan view of an arc chute construction of a contactor provided with my invention;

Fig. 4 is a vertical sectional view, on line IV—IV of the showing in Fig. 3;

Fig. 5 is a horizontal sectional view, on line V—V of Fig. 4;

Figs. 6 and 7 are schematic showings of a switch, shown in plan view and side elevation, respectively, provided with my invention;

Fig. 8 is a modification of my invention; and

Fig. 9 is a diagrammatic showing of the kind of blowout effect produced by the devices of the prior art.

In Figs. 1 and 2, I have shown a switch construction well known in the trade but modified to eliminate the blow-out electromagnet and further modified to provide a pair of permanent magnets 16 and 17, one at each side of the contact mechanisms, including the horizontally adjustable stationary contacts 11 and 12, and the movable contact 10.

The structure comprises the base 1 of insulating material carrying the contactor base 2 also of

2

insulating material. At the lower end of base 2 the U-shaped magnet 3 is mounted. This U-shaped magnet carries the coils 4 and 5 on the cores or legs of the U. The coils 4 and 5 when energized and in cooperation with the U-shaped magnet operate the armature 6 in a clockwise direction. The armature 6 is mounted on the contact actuating arm 7 pivoted at 8 and biased in a counterclockwise direction by the spring 9.

10 The upper end of arm 7 carries the movable contact 10 adapted to make contact either with stationary contact 11 or with stationary contact 12, depending on whether the coils 4 and 5 are energized or deenergized. The contacts 10, 11, 15 and 12 are disposed within the arc box 13 having the side walls 14 and 15.

In the prior art construction of the switch shown a relatively large north pole of an electromagnet was disposed at the outside surface of 20 one side wall, as side wall 14, and the south pole was disposed at the outside surface of the other side wall, as side wall 15. The magnetic field then produced is as indicated in Fig. 9. For a current flow as indicated by the arrows adjacent the contacts 111, 110 and 112, the arc between contacts 110 and 111 is blown upwardly, as shown by arc 101, but the arc 102 between contacts 110 and 112 is blown downwardly. For most switches, there are elements below the contacts that are not 30 to be subjected to an arc, or, what is usually worse and often the case, the elements below the contacts tend to maintain the arc. For still other switches, especially where considerable currents are to be interrupted special arc extinguishing 35 grids are provided above the contacts, as shown in Figs. 3, 4, and 5. If the arc is blown downwardly, such arc extinguishing grids are of no utility. To obtain the full benefit from the arc boxes provided on some contactors, and the arc 40 extinguishing grids provided on other contactors, I utilize an elongated permanent magnet 16 at one side of the contacts 10, 11, and 12 and a second elongated permanent magnet 17 at the other side of the contacts. The disposition is such that the 45 north pole of one magnet is opposite the south pole of the other magnet, and the south pole of the first magnet is opposite the north pole of the second magnet, with the magnet ends facing each other substantially in the planes of the pair 50 of stationary contacts 11 and 12.

With the arrangement just described the flux lines will be as shown in Figs. 6 and 7. It will be noted that the lines move clockwise about contact 210 as seen in Fig. 6 so that the arc is blown 55 upwardly between contacts 210 and 211 and is

blown upwardly between contacts 210 and 212. Contacts 210, 211, and 212 correspond to the contacts 10, 11, and 12 shown in Figs. 1 and 2, and correspond to contacts 30, 31, and 32 in Figs. 3, 4, and 5.

In Fig. 8, I show the permanent magnets in the general shape of a U with the stationary contacts 311 and 312 disposed between the legs of the U and the movable contact 310 disposed to oscillate between the stationary contacts 311 and 312. Again it will be noted that the flux is so related to the contacts that the arc is blown in the same direction regardless of whether the arc gap is between contacts 310 and 311, or between 310 and 312.

The arrangement shown in Fig. 8 has special merit for some applications where the magnetic air-gap is to be maintained at a minimum. In the showing of Fig. 8 the permanent magnet 316 need not necessarily be insulated from contact 311 nor does the permanent magnet 317 need to be insulated from contact 312. The magnets are thus not in position to provide a spurious arc path. The poles of the magnets may thus be in close proximity to the stationary contact and thus provide a better space factor for the transfer switch design.

In Figs. 3, 4, and 5, I show an arc extinguishing grid 33 associated with the contacts 30, 31, and 32. To get the full benefit of the arc extinguishing grid, I position the permanent magnet 35 at one side of the grid and the permanent magnet 37 at the other side of the grid and position the ends of the magnets and their polarities in the same relation as explained in connection with Figs. 1 and 2.

With the modern type of permanent magnets available there is no danger of not having sufficient flux.

From the foregoing it will be apparent that I have provided a permanent magnet blowout construction, for an oscillating contact type of contactor, that effects a blowout in the same direction regardless of which contacts are going through the opening operation.

While I have shown but two applications of my invention, other applications and other modifications of my invention are well within the true spirit and scope of my invention.

I claim as my invention:

1. In an electric switch, in combination, a base, a stationary contact mounted on the base, a second stationary contact mounted on the base a relatively short distance from the first stationary contact, a movable contact disposed between the stationary contacts and operable to oscillate between the contacts to interrupt an electric circuit at one stationary contact and close an electric circuit at the other stationary contact upon movement of the movable contact in one direction and to effect a similar operation with respect to the second and first stationary contacts upon movement of the movable contact in an opposite direction whereupon an electric arc is alternately drawn between the movable contact and the respective stationary contacts, a permanent magnet disposed with its north pole adjacent one side of the contacts, and a second permanent magnet adjacent the other side of the contacts with the poles of opposite sign facing each other substantially across the faces of the stationary contacts, whereby the arc drawn at the contacts is always blown in the same direction.

2. In an electric switch, the combination of a movable contact disposed between a pair of sta-

tionary contacts for coaction with the movable contact, a pair of permanent magnets disposed at the respective sides of the contacts with the poles so disposed that the flux is disposed across one face of the stationary contact in one direction and across the face of the other stationary contact in the opposite direction.

3. In an electric switch, the combination of, a pair of stationary contacts disposed to face each other across a relatively short distance, a movable contact disposed between the stationary contacts and operable to oscillate to thus alternately engage the stationary contacts, a pair of permanent magnets disposed one at each side of the contacts with the poles so disposed that the flux produced by the magnets encircles the movable contact.

4. In an electric switch, the combination of, a pair of stationary contacts disposed to face each other across a relatively short distance, a movable contact disposed between the stationary contacts and operable to oscillate to thus alternately engage the stationary contacts, an arc box of insulating material disposed to confine the arcs that may be drawn at the contacts, a pair of permanent magnets disposed one at each side of the contacts with the poles so disposed that the flux produced by the magnets encircles the movable contact.

5. In an electric switch, the combination of, a pair of stationary contacts disposed to face each other across a relatively short distance, a movable contact disposed between the stationary contacts and operable to oscillate to thus alternately engage the stationary contacts, an arc box of insulating material disposed to confine the arcs that may be drawn at the contacts, are extinguishing grids in the arc box, a pair of permanent magnets disposed one at each side of the contacts with the poles so disposed that the flux produced by the magnets encircles the movable contact.

6. In an electric switch, the combination of, a pair of relatively closely spaced stationary contacts, a movable contact disposed between the stationary contacts and operable to engage one or the other of the stationary contacts, a permanent magnet at one side of the contacts having a length sufficient that the poles are substantially opposite the stationary contacts, and a second permanent magnet similar in length and so disposed on the opposite sides of the contacts with poles of opposite polarity facing each other across the face of the stationary contacts and that the arc drawn at the contacts is blown upwardly.

7. In an electric switch, the combination of, a pair of relatively closely spaced stationary contacts, a movable contact disposed between the stationary contacts and operable to engage one or the other of the stationary contacts, a permanent magnet at one side of the contacts having a length sufficient that the poles are substantially opposite the stationary contacts, a second permanent magnet similar in length and so disposed on the opposite sides of the contacts with poles of opposite polarity facing each other across the face of the stationary contacts and that the arc drawn at the contacts is blown upwardly, and an arc box disposed over the contacts for confining the arc drawn at the contacts.

8. In an electric switch, the combination of, a pair of relatively closely spaced stationary contacts, a movable contact disposed between the

stationary contacts and operable to engage one or the other of the stationary contacts, a permanent magnet at one side of the contacts having a length sufficient that the poles are substantially opposite the stationary contacts, a second permanent magnet similar in length and so disposed on the opposite sides of the contacts with poles of opposite polarity facing each other across the face of the stationary contacts and that the arc drawn at the contacts is blown upwardly, an arc box disposed over the contacts for confining the arc drawn at the contacts, and arc extinguishing grids disposed in the box over the contacts to rapidly extinguish the arc.

9. In an electric switch, the combination of, 15 a pair of stationary contacts disposed to face each other over a relatively small distance, a movable contact disposed between the contacts

and in operation alternately coacting with the stationary contacts, and magnetic flux producing means including a first means for producing a flux in one direction across the face of one stationary contact and a second means for producing a flux in an opposite direction across the face of the other stationary contact whereby the flux encircles the movable contact.
